UNITED STATES PATENT OFFICE.

JAMES J. HINDE, OF SANDUSKY, OHIO.

PACKING-BOX.

SPECIFICATION forming part of Letters Patent No. 758,138, dated April 26, 1904.

Application filed June 10, 1902. Serial No. 110,991. (No model.)

To all whom it may concern:

Be it known that I, JAMES J. HINDE, a citizen of the United States, residing at Sandusky, in the county of Erie and State of Ohio, have 5 invented certain new and useful Improvements in Packing-Boxes, of which the following is a specification, reference being had therein to the accompanying drawings.

The invention relates to improvements in 10 packing-boxes intended for use in the shipment of fragile articles, and more especially designed for use in packing lamp-globes and other like articles.

It is the object of the invention to obtain a 15 construction in which the globe or other article is held suspended within the package, so that it will not come directly in contact with external objects, thereby preventing all danger of breakage.

20 The invention consists in the construction hereinafter described and claimed.

In the drawings, Figure 1 is a perspective view of the package. Fig. 2 is a section through Fig. 1, showing an outer case applied 25 thereto; and Fig. 3 is a top plan view.

It is one of the objects of the invention to provide means for securely holding the article within the case which will permit of easily packing or unpacking the same.

30 It is a further object to guard the bearing portions from contact with external objects.

These two objects are accomplished by the construction shown, in which A is a casing formed of paper-board or other like material. 35 This casing is of tubular form and may be quadrilateral or any other polygonal shape. Each of the sides α is bent inward, so as to form bearings for supporting the contained article. In order to securely hold the article

40 in place, the sides α are preferably partially cut away at b , thereby forming seats for the article. Thus where the article is of globular form, as shown, it will have an annular bearing on each of the four sides of the casing and 45 will thereby be held securely in position.

To retain the casing in form, a band, such as B, is arranged around the same. This band is preferably of sufficient width to cover the cut-away portion b and to protect the annular bearings upon the article from contact

with external objects. The height of the casing is such that the article when in engagement with its bearings will be held within the ends of the casing, so as to be out of contact with objects above or below the same.

55

In packing the article may be readily inserted within the casing A, as the sides α thereof are free to spring outward whenever the band B is removed. After the article is in engagement with the bearings the band is 60 placed in position and serves to hold the sides α in their bent form. The unpacking may be as readily effected by slipping off the band B, after which the article may be drawn out from the casing A.

65

If desired, an outer protecting-casing, such as C, may be placed around the casing A, which outer casing may be either a formed box or merely a wrapping of paper-board. Where the outer casing is used, the article 70 will be suspended therein out of contact with all of the sides, so that it will be effectually guarded from external injury.

In place of cutting away a portion of the side to form the seat for the article said side 75 may be merely slotted for that purpose, or the bearing may be made in any other suitable way.

What I claim as my invention is—

1. A packing-case for spheroidal bodies 80 comprising a polygonal open-ended casing adapted to freely receive the articles to be packed therein and having an annular seat for said article on the inner face of one of its sides, and a surrounding band for holding 85 said bearing side in an inwardly-bent form, whereby said seat is pressed against the contained article and will hold the latter from endwise movements.

2. A packing-case comprising a casing having a flat centrally-apertured side thereof bent at an angle inward to form an annular seat for the contained article and a surrounding band for holding said side in its bent form.

3. A packing-case comprising a polygonal 95 casing having the sides thereof centrally apertured and bent inward to form annular seats for the contained article and an annular surrounding band for holding said sides in their bent form.

100

4. A packing-case comprising a quadrilateral open-ended casing having each of the sides thereof bent inward and partially cut away to form an annular seat for the contained article
5 and a surrounding band for holding said sides in their bent form and covering said cut-away portions.

In testimony whereof I affix my signature in presence of two witnesses.

JAMES J. HINDE.
